UNITED STATES PATENT OFFICE

127,513

DESIGN FOR A MANICURE CASE

Hamilton C. Bates, Chester, Conn.

Application April 8, 1941, Serial No. 100,232

Term of patent 3½ years

To all whom it may concern:

Be it known that I, Hamilton C. Bates, a citizen of the United States, residing at Chester, in the county of Middlesex and State of Connecticut, have invented a new, original, and ornamental Design for a Manicure Case, of which the following is a specification, reference being had to the accompanying drawing, forming part thereof.

The figure is a perspective view of a manicure case, showing my new design.

The bottom of the case is substantially plain.

I claim:

The ornamental design for a manicure case, as shown and described.

HAMILTON C. BATES.
